UNITED STATES PATENT OFFICE.

ANDREW CRAWFORD PATRICK, OF JOHNSTONE, SCOTLAND.

PLATE BENDING AND STRAIGHTENING MACHINE.

No. 807,088.

Specification of Letters Patent.

Patented Dec. 12, 1905.

Application filed February 1, 1905. Serial No. 243,701.

To all whom it may concern:

Be it known that I, ANDREW CRAWFORD PATRICK, a subject of the King of the United Kingdom of Great Britain and Ireland, and a resident of Johnstone, county of Renfrew, Scotland, have invented certain new and useful Improvements in Plate Bending and Straightening Machines, of which the following is a specification.

This invention relates to plate-bending machines; and it has for its object to adapt such machines for resetting or straightening plates which in passing through the rolls have been bent beyond the required curvature, and this by merely returning the plate through the rolls instead of, as is usual in three-roller machines, having to run the plate clear of the rolls and enter it again in inverted position.

The invention is illustrated, by way of example, in the accompanying drawings, in which—

Figure 1 is a front elevation, and Fig. 2 an end elevation, of one embodiment of the improved plate-bending machine as adapted for bending and also for resetting or straightening plates; and Fig. 3 is an end elevation showing a modification adapted mainly for straightening plates.

As shown by the drawings, the improved machine comprises side cheeks A A, in which are housed the ends of the three usual rollers B B B for bending plates, the said rollers being driven and adjusted by the usual construction of gearing, as shown. A supplemental roller B' is added to the three-roller bending-machine and is so carried on the side cheeks A at the entrance side of the rolls that it may be lowered down clear of the entering-plate during the bending operation, which is effected by the three rolls B B B in the usual way, or it may be raised into such position that, on returning through the rolls a plate which has been overset, the fourth roller B' bears on the plate and more or less tends to flatten it. Thus when the machine is required to be used for the usual work of plate-bending the fourth roller B' is lowered into a position in which its upper side is not above the level of the top side of the two driven bottom rollers B B. If a plate has been overset and required to be flattened or straightened out, the fourth roller B' is lowered or run up to about the position shown

at Fig. 1, so that its bottom surface clears the curved plate in the machine, and as the plate is returned through the rolls B B toward the fourth roller B' the curve in the plate is partially or wholly taken out by depressing said fourth roller to the required degree. While the machine is thus particularly adapted for resetting overset plates, it may also be used for finishing the plate perfectly flat and for straightening bent or buckled plates by suitably setting the fourth roller and using the machine as an ordinary plate-straightening machine.

In the heavier class of machines the journal ends b' of the roller B' are housed in inclined guideways C in the side cheeks, so that the roller is run up or down, as indicated by dotted lines at Fig. 2, by screws D or like means, the screw-shafts D in the example shown being operated by worm-wheels E thereon, driven from worms F on a shaft G, furnished with a hand-wheel H.

When the machine is to be used only for straightening bent or buckled plates, the modification shown at Fig. 3 is employed. In this case the additional roller B' is supported in end bearings b'', fitted to slide vertically in the side cheeks A, the position of the roller being adjusted to suit different thicknesses of plates by means of screw-shafts D D at each end, operated by a worm-wheel nut d' from a worm-shaft E'. This machine may be used for bending plates, but only to such a curvature as will permit the plate to clear the roller B', which is then raised, so that its lower edge is above the level of that of the top roller B.

The four-roller machines herein described have the advantage over the ordinary seven-roller mangles or flattening-machines not only of being less costly in construction, but that they deal more effectively with the flattening of plates, owing to the fact that in the four-roller machine the plate can be bent up round the top bending-roller, and in running it back under the straightening-roller to take the set out of the plate, it is more effectively dealt with than in passing it several times back and forward through the ordinary seven-roller machine.

Having now described my invention, what I claim, and desire to secure by Letters Patent of the United States, is—

The combination of a plate-bending ma-

chine comprising a set of three bending-rollers and means for operating the same, of a supplemental roller normally held in an inoperative position, guides for said supplemental roller, and means for moving said roller in said guides to bring it in line with any one of said bending-rollers to form a four-roller plate-straightening machine.

In testimony whereof I have signed my name to this specification in the presence of two subscribing witnesses.

ANDREW CRAWFORD PATRICK.
